(57) **CLAIM**

The ornamental design for a portable light hanger, as shown and described.

DESCRIPTION

FIG. 1 is a front view of a portable light hanger showing the new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top front perspective view thereof;

FIG. 8 is a bottom front perspective view thereof;

FIG. 9 is a top rear perspective view thereof;

FIG. 10 is a bottom rear perspective view thereof;

FIG. 11 is a front view of said portable light hanger shown in an environment of use coupled to a light;

FIG. 12 is a rear view of said portable light hanger shown in an environment of use coupled to a light;

FIG. 13 is a bottom front perspective view of said portable light hanger shown in an environment of use coupled to a light;

FIG. 14 is a front view of said portable light hanger shown in an environment of use secured to an electrical receptacle with a fastener;

FIG. 15 is a front view of said portable light hanger shown in an alternate configuration of use, in an environment of use coupled to a light;

FIG. 16 is a rear view of said portable light hanger shown in an alternate configuration of use, in an environment of use coupled to a light; and,

FIG. 17 is a front view of said portable light hanger shown in an alternate configuration of use, in an environment of use secured to an electrical receptacle with a fastener.

The broken lines shown in the drawings depict portions of the portable light hanger that form no part of the claimed design. The additional broken lines shown in FIGS. 11-17 illustrate environment and form no part thereof.
